UNITED STATES PATENT OFFICE.

THOMAS H. B. VAN HOOZER, OF COMANCHE, TEXAS.

CHURN-COVER.

SPECIFICATION forming part of Letters Patent No. 701,284, dated May 27, 1902.

Application filed August 17, 1901. Serial No. 72,357. (No model.)

To all whom it may concern:

Be it known that I, THOMAS H. B. VAN HOOZER, a citizen of the United States, residing at Comanche, in the county of Comanche 5 and State of Texas, have made certain new and useful Improvements in Churn-Covers, of which the following is a specification.

My invention is an improvement in churn-covers seeking to provide a novel construction of cover which will embody a closed dead-air space above the body of the churn, a guide-tube for the dasher-rod, and the special construction at the outer edge of the base of the cover by which to provide a channel to fit 15 upon the upper edge of the churn-body; and the invention consists in certain novel constructions and combinations of parts, as will be hereinafter described and claimed.

In the drawings, Figure 1 is a side view, 20 and Fig. 2 a sectional view, of my improved cover as applied to a churn-body. Fig. 2^a is a detail sectional view of one edge of the cover at the base thereof. Fig. 3 is a bottom plan view of the cover; Fig. 4, a top plan view of 25 the cover; Fig. 5, a detail perspective view of one of the retaining-clasps; and Fig. 6, a detail perspective view of a slightly-different form of retaining-clasp, all of which will be described.

30 In carrying out my invention I form the cover with a conical or tapered side A and the base or bottom B, the latter being provided centrally with an opening in alignment with an opening in the apex of the cone A and the 35 guide-tube C being arranged to extend longitudinally through the center of the cover so it will form a guide for the dasher-rod in the operation of the device, as will be readily understood. In addition to forming the bracing-support for the lower end of the guide-tube C the bottom B forms within the cover a dead-air space at D, which aids in keeping the milk from heating and also strengthens the cover at its base. At the base of the cone 45 A, I provide an outwardly-extending flange E, which is provided at its outer edge with a depending flange F, and an inner depending flange G is arranged within the flange F and spaced apart therefrom sufficiently to form 50 the channel E' to fit upon the upper edge of the churn-body, as best shown in Fig. 2. It will be noticed that the flange G unites at its

upper end with an inwardly-projecting flange G', which is lapped against and secured to the bottom B by soldering or any other suitable 55 manner. It will also be noticed that the flange G is located below the junction of the outwardly-projecting flange E with the tapered side A of the conical top, so the channel E' underlies the flange E. 60

In practice the cover is placed upon the top of the ordinary churn-body or jar H, as shown in Figs. 1 and 2, and is provided with the spring-clasps I, secured at their upper ends to the cover and having their lower ends 65 at I' arranged to spring beneath the projecting bead H² on the outer side of the body H near its upper end. The clasps I may be made of a single thickness of material, as shown in Fig. 6; but I prefer the construction 70 shown in Figs. 1, 2, and 5, in which the lower end of the clasp is doubled upon itself at I² and is provided at the upper end of the doubled portion with an upwardly-projecting handle-wing I³, so the clasp can be readily released from engagement with the churn-body. 75 The construction is simple, inexpensive, affords the proper guide for the dasher-rod, furnishes a dead-air chamber above the churn-body, includes a channel construction to inclose the upper edge of the churn-body, can be readily applied to and removed from the churn, and arranges the channel in such manner as to secure a strong firm connection with the churn-body. By providing the flanges to 80 fit within and without the upper edge of the churn-body I avoid all danger of the contents being splashed out of the churn-body between the same and the cover, and thus increase the cleanliness of the churning operation. 85 90

Having thus described my invention, what I claim as new, and desire to secure by Letters Patent, is—

1. The churn-top herein described comprising the hollow cone, the outwardly-projecting flange at the lower end of the tapered sides, the depending flange at the outer edge of said first flange, the bottom extending across the base of the cover forming the dead-air space, the tubular guide for the dasher-rod extending between the center of the bottom and the apex of the cover, and the depending flange located within and spaced apart from the outer depending flange forming an annular cham- 95 100

ber to fit upon the upper end of a churn-body, said inner depending flange being provided at its upper edge with a rim-flange secured to the bottom of the cover and the clasps carried by the cover whereby to secure said cover in place upon a churn-body, substantially as set forth.

2. The churn-cover herein described comprising the base-plate provided at its outer edge with a depending flange overlapping the outer side of the churn-body, the flange depending from the base-plate and located within and spaced apart from the outer flange and arranged to lap within the churn-body, the

central tubular guide secured to the base-plate and projecting upwardly from the base-plate and opening at its lower end through said base-plate, and the rigid hollow cone secured at its larger or base end to the base-plate and at its upper end to the tubular guide and forming, with the base-plate, an air-space surrounding the tubular guide substantially as set forth. 15 20
